UNITED STATES PATENT OFFICE.

HOLGER J. NIELSEN AND CHARLES J. BORGLIN, OF SAN FRANCISCO, AND LUDVIG C. A. SOEBORG, OF ALAMEDA, CALIFORNIA, ASSIGNORS TO BEAR MILLING AND MINING COMPANY, OF SAN FRANCISCO, CALIFORNIA, A CORPORATION OF CALIFORNIA.

CONVEYER.

1,069,163.

Specification of Letters Patent.

Patented Aug. 5, 1913.

Original application filed November 25, 1911, Serial No. 662,296. Divided and this application filed May 7, 1912. Serial No. 695,691.

To all whom it may concern:

Be it known that we, HOLGER J. NIELSEN, CHARLES J. BORGLIN, and LUDVIG C. A. SOEBORG, the former a subject of the King 5 of Great Britain and the two latter citizens of the United States, the two former residing at San Francisco and the latter at Alameda, in the counties of San Francisco and Alameda, respectively, and State of 10 California, have invented certain new and useful Improvements in Conveyers, of which the following is a specification.

Our present invention relates to conveyers well adapted for use with ore concentrators, and the like, as disclosed in our co-pending application filed November 25th, 1911, Serial No. 662,296, from which the present application has been divided out.

The principal objects of our invention are, 20 first, to provide a conveyer which has a relatively large field of movement depositing the material to be conveyed at a certain or central point without bodily moving the conveyer and appertaining devices, and 25 whereby the receiving end of the conveyer may be moved as the workings progress the point of deposition remaining practically the same, second, to provide means for driving the conveyer and permitting movement 30 of the conveyer frame without stopping the drive means or readjusting the same; and, third, to construct the conveyer wherever practical, of standard materials thus facilitating construction and reducing the cost 35 thereof to a minimum.

In the drawings, forming a part of this specification: Figure 1 is a top plan view of the conveyer embodying our invention. Fig. 2 is a side elevation of the same. Fig. 3 is 40 an end elevation of the conveyer, at its delivery end, and a portion of the supporting track therefor. Fig. 4 is a bottom plan view of the supporting carriage used in connection with the conveyer.

45 Similar characters refer to similar parts throughout the views.

The conveyer proper includes a suitable frame, which may be built up of longitudinal members 2, struts 3, and diagonals 4. 50 The delivery end of this frame has bearings for a shaft 5, suitably supported as will be subsequently described, upon which is keyed

or otherwise carried a conveyer belt drum 6. The receiving end of the frame carries longitudinally movable bearing blocks 7 for 55 a shaft 8, upon which is carried a second belt drum 9, each bearing block being adjusted by a set screw 10. A plurality of guide rollers 11 are suitably carried by the struts 3 and alined to support the upper 60 portion of the belt 12 which serves for carrying the material deposited thereon. This belt 12 is trained about the drums 6 and 9, which together with guide rollers 11 are preferably dished peripherally to give the 65 belt 12 a concavo-convex section when passing through the zone of transportation. A plurality of secondary guide rollers 13 are also provided, suitably carried by struts 3, to support the under run of belt 12. 70

With the view of elevating the delivery end of the conveyer frame, we provide track framework including uprights 14 and horizontal members 15, suitably secured together, a track 16 being mounted upon such 75 frame. This track 16 is designed to support and guide a carriage, designated generally at 17, which is operatively connected to the delivery end of the conveyer, and is preferably circular in plan, although it may 80 be arc shaped according to the field of magnitude of the angle of movement it is desired to provide for the conveyer proper. The track 16 has preferably an I section, and therefore may be provided from a 85 standard rolled section. In the case of an I section, the top flanges of the track serve as the supporting tread and the web thereof as the guiding tread.

The carriage 17 includes a base plate 18 90 having lugs 19 positioned to extend laterally at the side of the web of the track 16 in close proximity to the outer margins of the upper flanges thereof. These lugs carry a plurality of supporting rollers 20 riding 95 upon the upper flanges and guide rollers 21 riding upon the web at both sides thereof. Thus the base plate 18 is supported to ride upon the track and prevent it from becoming displaced with respect thereto. 100

Carried by the plate 18, superadjacent thereto, are bearing blocks 22 for the before mentioned shaft 5, whereby the conveyer frame is pivotally connected to the carriage

17, to swing in a vertical plane. Bearing blocks 23 hung in an idler 24 are provided for a purpose to be subsequently disclosed. The shaft 5 has keyed, or otherwise secured thereto, a driven pulley 25 for rope belting used as a means for imparting movement to the drums 6.

Certain of the horizontal frame members 15 may carry a beam 26 which supports a 10 step bearing 27 for a vertically disposed drive shaft 28, which is supported concentric to the arc of the track 16 serving as a support for the carriage 17. A stabilizing bearing for the shaft 28 may be provided in a bar 15 29 suitably secured to track 16. This shaft 28 carries a driven pulley 30, actuated through belt 32 from any suitable source of power, and a driving pulley 31 in operative relation to the said driven pulley 25, the pulley 31 being rotatable in a horizontal plane.

Movement from pulley 31 is transmitted to pulley 25 by means of endless rope belting 33, in such a manner as to always be in operative motion transmitting relation regardless of angle of the longitudinal axis of the conveyer frame to the carriage 17, or the position of the conveyer frame and its carriage 17 to the drive shaft 28, within the bounds of movement provided for by track 16. This 25 rope belting is trained successively, starting from pulley 31, around pulley 25, back and around pulley 31, then over idler 24, down and around an idler 34, weighted as at 35, then up and over pulley 25 and back to the 30 starting point at pulley 31. It will be seen that the weighted idler takes up the stretch of the rope and keeps it always in the same tension, still permitting movement of the carriage about an arc described concentric 35 to the axis of shaft 28. Below the discharge end of the conveyer proper, and preferably carried by the track 16, is a funnel-like hopper 36, which flares out so as to receive the material, carried by the conveyer brake belt, 40 at any practical position of the conveyer proper, provided for by the carriage 17 and track 16.

It is obvious that the construction of the conveyers and track elevating framework 50 hereinbefore described may be modified, as

circumstances may require, without departing from the spirit of our invention.

The operation of the device is as follows: Assuming, as for example, the conveyer is used for conveying mineral bearing earth 55 substances to a concentrator, the track frame is positioned in close proximity to the concentrator and in a convenient position adjacent the working. As the earthy substance is mined, or in other words, as the work progresses, the conveyer proper is moved with its receiving end to be in a position such as to receive the material directly as it is mined. In the device as disclosed, the conveyer proper has an arc of movement of, somewhat 60 less than 180 degrees, limited by the cross bar 29, however, it is obvious that the construction might be such as to permit an angular movement of a magnitude greater or smaller than this, the hopper being so constructed as to receive the material from the delivery end of the conveyer proper regardless of its position about the track.

We claim:

In a conveyer structure, the combination 75 with suitable framework, a horizontally disposed arc shaped track, a conveyer provided with movable conveying means, a carriage operatively connected to said conveyer at its delivery end, mounted upon said track, a 80 driven pulley carried by said carriage for actuating the movable conveying means of said conveyer, an idler carried by said carriage, a driven pulley revoluble in a horizontal plane with its axis coinciding with the 85 center from which the arc of said track is struck, a weighted idler, and an endless rope belt trained about said driving pulley, driven pulley, first mentioned idler and weighted idler, substantially as and for the purpose 90 set forth.

In testimony whereof we affix our signatures in presence of two witnesses.

HOLGER J. NIELSEN.
